TELEVISION SYSTEM

Vladimir K. Zworykin, Philadelphia, Pa., assignor to Radio Corporation of America, a corporation of Delaware

Application March 30, 1935, Serial No. 13,792

2 Claims. (Cl. 178—7.2)

My invention relates to improvements in television systems and the method of operation thereof.

In developing picture signals for television transmission, a scanning device is exposed to light from the view or object for transmission. One form of scanning device for this purpose comprises a tube having a mosaic, photosensitive screen upon which an image of the view is projected through a suitable lens system. The tube is provided with means for developing a ray of electrons and directing the same at the screen. The ray is deflected simultaneously in different directions to scan the screen, whereby the picture signals are developed for supply to an amplifier and transmitter. In such a system, it has been found that the cathode ray transmitter tube operates most efficiently under a given condition of illumination by light from the view for transmission and, for this reason, manual adjustments have been made heretofore for the purpose of maintaining the tube at its most efficient point of operation as the light intensity, to which the photosensitive screen is exposed from the view, might vary due to occurring changes at the transmitting station such as a change in light intensity from the view, or a change in the distance between the transmitting tube and the view.

With the foregoing in mind, it is one of the objects of my invention to provide an improved television transmitting system of the character referred to in which means are provided for automatically controlling the light intensity to which the scanning device is exposed from the view, whereby the device is maintained substantially at its most efficient point of operation.

Another object of my invention is to provide a system of the type described wherein electrical means are utilized for correlating the sensitivity of the scanning device to the degree of illumination of the object being scanned.

Other objects and advantages will herein-after appear.

In accordance with my invention, the scanning device and the circuits associated therewith are utilized to generate an electrical effect which varies with occurring variations in the light intensity to which the device is exposed from the view for transmission. This effect is, in turn, utilized to control the light intensity to which the scanning device is exposed from the view, in the sense that the light intensity is made to decrease upon an increase in the electrical control effect and to increase upon a decrease in such effect.

More specifically, in accordance with my invention, a cathode ray tube of conventional design is utilized to develop the picture signals, and an adjustable shutter device is interposed between

the photosensitive screen of the tube and the view or object for transmission to control the light intensity to which this screen is exposed from the view. An electrical effect is developed which varies with occurring variations in the light intensity from the view, and is used to cause opening or closing movement of the shutter device, as might be required, to maintain the value of light intensity on the screen substantially at the correct point for most efficient operation of the tube.

My invention resides in the improved construction and method of operation of the character hereinafter described and claimed.

For the purpose of illustrating my invention, several embodiments thereof are shown in the drawings, wherein

Figure 1 is a simplified, diagrammatic view of a television transmitting system constructed and operating in accordance with my invention; and

Figs. 2, 3, 4, 5, 6 and 7 are views similar to Fig. 1, showing different modifications.

In Fig. 1, the reference numeral 10 designates a scanning device in the form of a cathode ray tube of conventional design, comprising a tube 12 provided with a mosaic photosensitive screen 14 and with means in the form of an electron gun 16 for developing a stream or ray 18 of electrons and directing the ray at the screen. The screen comprises a mica sheet provided on the front face 20 thereof with a large number of minute, metallic, photosensitive elements, spaced and insulated from each other. The screen is provided on the back face 22 thereof with a metallic layer to which a connection 24 is made. In operation, an image of the object or view 26 for transmission is projected by a lens system 28 onto the photosensitive surface 20 of the screen. In this way, individual, electrostatic charges are developed over the surface of the screen, the value of the charge or charges at any elemental area being proportional to the light intensity on that area at the instant.

The ray 18 of electrons is deflected horizontally at a relatively high rate by coils 30 and 32 and is simultaneously deflected vertically at a relatively low rate by coils 34, whereby the ray is caused to scan the photosensitive surface of the screen 14. In this way, picture signals are developed and supplied by the connection 24 to an amplifier 36 and a transmitter 38.

For the purpose of controlling the value of light intensity to which the screen 14 is exposed from the view, a shutter device in the form of an adjustable iris diaphragm 40 of conventional design is associated with the lens system 28. The opening in the diaphragm 40 is made larger or smaller upon rotation of a gear 42 which meshes with a pinion 44 fixed on a shaft 46 driven by a D. C motor 48. The motor 48 is

provided with separately excited field coils 48, as represented in the drawings, and is also provided with a suitable brake 50 which places a relatively light, initial load on the motor.

5 The amplified picture signals from the amplifier 34 are supplied by a connection 52 to the grid of a relatively high impedance electron tube 54 of the type identified in the trade as "RCA 57". The tube 54 has a self-bias resistor 56 of 10 relatively high resistance. This resistor is shunted by a condenser 58 of relatively high capacity. In operation, a D. C. voltage is developed across the resistor 56 which varies substantially in accordance with occurring variations 15 in the average peak A. C. voltage on the grid of the tube 54. This tube and its associated circuits operate at a peak voltmeter. An electrical effect, accordingly, is developed which varies with occurring variations in the light intensity to which the screen 14 is exposed from the view. This electrical effect is amplified by a control amplifier 60 to develop a voltage across 20 a resistor 62 in the output circuit of a tube 64 forming part of the amplifier.

25 The motor 46 is supplied from the amplifier 60 through connections 66 and 68, a battery 70 being connected as shown in the connection 68.

Adjustments are made initially so that when 30 the value of light intensity to which the screen 14 is exposed is substantially correct for most efficient operation of the electron scanning device 10, the potential difference V_m between the potentials V_a and V_b is substantially zero, or at least so small as to prevent operation of the 35 motor 46 against the drag or load provided by the brake 50. If illumination of the screen 14 should increase, the potential V_a increases correspondingly to give a value to the potential V_m to cause rotation of the motor armature in the 40 proper direction to cause closing movement of the iris diaphragm 38. This action continues until sufficient light is cut off from the screen 14 to bring the value of the potential V_a back to the point whereat the potential V_m is at least 45 low enough to permit the brake 50 to stop the motor. If illumination of the screen 14 should decrease below the desired value for most efficient operation, the reverse action takes place. That is, the potential V_a decreases and becomes 50 less than the potential V_b , whereby the polarity across the lines 66 and 68 is changed and the potential V_m becomes at least sufficient to cause reverse rotation of the motor to cause opening 55 movement of the diaphragm 38. This action continues until the screen 14 is again exposed to the required light intensity from the object for most efficient operation, at which time the potential V_m again becomes zero, or at least decreases to a value insufficient to cause rotation 60 of the motor against the braking action of the brake 50.

The brake 50 provides for sufficient time lag to prevent actuation of the diaphragm 38 for 65 every slight, momentary change in illumination of the screen 14.

From the foregoing it will be seen that variation in the peak picture signals, with occurring 70 variations in illumination of the screen 14, is utilized to develop an electrical control effect which varies in a similar manner and operates to control adjustment of a shutter device interposed between the scanning device and the view, whereby the value or degree of illumination of 75 the scanning device is changed accordingly to

bring it back to the point for most efficient operation.

In Fig. 2, the operating action is the same as that in Fig. 1 except that the electrical control effect is obtained from the second anode 72 of the transmitting tube. The principle involved resides in the fact that the photoelectric current, taken from the anode 72, varies proportionally to occurring variations in the degree of illumination of the screen 14. For the purpose of 10 adjusting the diaphragm 38, a solenoid 74 is utilized instead of the motor in Fig. 1. The solenoid is connected by levers 76 and 78 to the actuating member of the iris diaphragm 38. A piston 80 is connected as shown to the solenoid, 15 and is disposed within a cylinder 82 provided at one end with a vent opening 84. A coil spring 86 is disposed between the piston and the other end of the cylinder. Adjustments are made initially so that the degree of illumination of the 20 screen 14 is correct for most efficient operation, in which case the voltage across the lines 66 and 68 is sufficient to operate the solenoid so that it holds the diaphragm 38 open at the right point, against the action of the spring 86 which 25 is compressed. If the degree of illumination of the screen 14 drops below the desired point, the potential across the lines 66 and 68 will drop correspondingly to lessen the downward pull of the solenoid 74. The spring 86 is then effective to 30 cause movement of the lever 76 to open the diaphragm 38 until illumination of the screen 14 is again sufficient to cause the downward pull of the solenoid 74 to balance the upward force due to the spring 86. If the degree of illumination 35 of the screen increases beyond the point desired, the reverse action takes place. That is, the potential across the lines 66 and 68 increases so that the downward pull of the solenoid 74 is sufficient to further compress the spring 86, 40 whereby the diaphragm 38 is caused to close. This action continues, as will be well understood, until the degree of illumination of the screen 14 is again such that the downward pull of the solenoid 74 is balanced by the upward force due 45 to the spring 86.

The piston 80 and cylinder 82 operate as a dash-pot and, with the vent 84 at the proper size, serve the same purpose as the brake 50 in Fig. 1 to provide a time-lag. 50

In the system shown in Fig. 3, both the control electrical effects in Figs. 1 and 2 are utilized to control the motor 46 for adjusting the diaphragm 38. That is, both the effects of variation of the peak picture signals and the photoelectric current from the second anode 72 are utilized for obtaining the automatic control of light on the screen 14. In this figure, the various parts and connections corresponding, respectively, to those in Figs. 1 and 2, are designated by the same reference numerals as the latter. In Fig. 3, it is proposed to employ variable resistors 88 and 90, connected in the circuit as shown, for the purpose of adjusting the amplitude of the control amplifier 60. Also, the control signals from the anode 72 are amplified by an amplifier 91 before being supplied to the amplifier 60. 60

In Fig. 4, the control electrical effect is obtained by supporting a photoelectric cell 92 adjacent the screen 14 so that it is exposed to the light emitted therefrom. In this way, an electrical control effect is developed which increases when the degree of illumination of the screen 14 exceeds that required for most efficient op- 7

eration, and decreases when the degree of illumination of the screen falls below the desired value. The control current from the cell 92 is amplified by the control amplifier 60 and is effective to cause operation of the motor 46 in the same manner and for the same purpose as in Fig. 1.

The arrangement and operating action of the system shown in Fig. 5 is the same as that in Fig. 2 except that an additional connection 94 is made from the output of the control amplifier 60 to the control grid 96 of the electron gun. The polarities are such that as conditions change to call for further opening of the diaphragm 38, the bias on the grid 96 is decreased to increase the intensity of the scanning ray correspondingly. When conditions change to call for closing of the diaphragm 38, the bias on the grid 96 is increased correspondingly to decrease the intensity of the scanning ray.

In Fig. 6, the scanning device is represented as being in the form of a cathode ray tube of conventional design in which the mosaic, photosensitive screen 14a is two-sided. That is, the minute, metallic elements, represented at 93, pass through the supporting mica sheet, and are photosensitive on the side removed from the electron gun. In operation, an image of the view is projected onto the photosensitive surface of the screen 14a through a wire mesh 100 which is maintained at a potential positive with respect to the potential of the screen 14a. The principle involved resides in the fact that the sensitivity of the tube varies upon variation in the potential on the anode 100. The control electrical effect is obtained, as in Fig. 2, from the second anode 72a, and is supplied to the control amplifier 60. The potential on the anode 100 is dependent upon the voltage across the resistor 104 in the output circuit of the amplifier 60.

In operation, adjustment of the potentiometer 106 is made to bias the anode 100 to the point for most efficient operation. If the degree of illumination of the screen 14a decreases below this point, the voltage across the resistor 104 charges to cause the potential on the screen 100 to become more positive with respect to the potential on the screen 14a. In this way, the sensitivity of the tube is increased until the point is reached whereat the tube is again operating most efficiently. If the degree of illumination of the screen 98 increases beyond the desired point, the automatic control action is just the reverse. That is, the potential on the anode 100 becomes less positive with respect to the potential on the screen 14a to decrease the sensitivity of the tube, until conditions are again restored to the point for most efficient operation.

In Fig. 7, the transmitting tube is shown as being provided with an auxiliary source of electrons, designated generally by the reference numeral 108, and comprising a filament 110, a grid 112, and an anode 114. By this means, electrons in the form of a spray are directed at the screen 14 to supply a bias thereon. In operation, as the degree of illumination of the screen 14 decreases below the point for most efficient operation, the control signals, which in this case are taken from the second anode 72 and supplied to the control amplifier 60, are effective to cause the potential on the anode 114 to become less positive, whereby the velocity of electrons from the source 108 decreases correspondingly. The screen 14 then collects more primary electrons than it

emits secondary electrons, so that the individual, photosensitive elements become more negative, and the tube becomes correspondingly more sensitive.

When the degree of illumination of the screen 14 increases beyond the desired point, the action is just the reverse. That is, the potential on the anode 114 becomes more positive to cause a corresponding increase in the velocity of electrons from the source 108. Since the electrons from this source now strike the screen 14 at a greater velocity, more secondary electrons are emitted therefrom than primary electrons, and the minute, photosensitive elements become less negative. The sensitivity of the tube is thereby decreased until it is again operating at the desired point.

The values of operating potentials, resistance and capacity may be substantially as designated in Fig. 1. These values, however, are not critical, and may be varied over a substantial range, as might be required.

From the foregoing it will be seen that I have provided an improved television transmitting system and method of operation thereof in which adjustments are automatically made as the degree of illumination of the scanning device might vary due to change in illumination of the object, or change in the distance of the transmitting tube from the object, and that in this way the system is maintained at substantially the point for most efficient operation thereof.

It will be understood that modifications, other than those disclosed, are possible without departing from the spirit of my invention or the scope of the claims.

I claim as my invention:

1. In a television system, a cathode ray transmitter tube comprising a screen which is so sensitized that it emits electrons when an image is formed thereon, said tube also comprising an electrode positioned to collect said electrons and further comprising means for producing a cathode ray, means for scanning said screen by said cathode ray whereby picture signals are developed, a connection including an impedance unit between said collector electrode and said ray producing means, a shutter device for controlling the intensity of said image, and means including a direct current amplifier connected between said impedance unit and said shutter for decreasing the intensity of said image in response to an increase in the voltage drop across said impedance unit.

2. In a television system, a cathode ray transmitter tube comprising a screen which is so sensitized that it emits electrons when an image is formed thereon, said tube also comprising means for producing a cathode ray, means for scanning said screen by said cathode ray whereby picture signals are developed, means for producing an electrical effect which varies in response to occurring variations in the intensity of said image, a shutter device for controlling the intensity of said image, means for controlling said shutter device in accordance with said electrical effect in the sense that the shutter device is caused to close in response to an increase in the intensity of said image, and means for simultaneously increasing the intensity of said cathode ray in response to an increase in the intensity of said image.

VLAUDIMIR K. ZWORYKIN.
